AUTOMATIC EJECTOR MECHANISM FOR STOCK CUTTING MACHINES
Carl Thumm, Lombard, Ill., assignor to Michle-Goss Dexter, Inc., Chicago, Ill., a corporation of Delaware
Original application Nov. 7, 1956, Ser. No. 620,928, now Patent No. 3,033,067, dated May 8, 1962. Divided and this application Feb. 13, 1962, Ser. No. 173,075
6 Claims. (Cl. 83—90)

This invention relates generally to ejector mechanisms, and more particularly to novel mechanisms for ejecting the last cut stock section of an automatic cutting machine. This patent application is a division of my copending case Serial No. 620,928 filed November 7, 1956, now Patent No. 3,033,067 and assigned to the same assignee hereof.

In a cutting machine of the type herein, a stack of paper sheets is supported on a horizontal table. A reciprocable knife blade is provided at the front end of the machine to execute transverse cuts on the paper stack in a predetermined manner. Reference is made to Patent No. 2,570,873 as typical of such type of machine. A clamp for holding the paper stack intact is arranged adjacent the knife blade, to act upon the stack as it is being transversely cut. A back gauge is provided at the rear end of the stack, movable towards the front, along the table on which the stack is supported. The back gauge is moved in a predetermined manner to push the stack forward between cutting operations of the knife. A start-stop program device is generally related with the back gauge to automatically start its movement and stop it at predetermined positions during the cutting cycles of the knife assembly. Such back gauge system in a cutting machine is illustrated and described in Patent No. 2,487,031 entitled "Automatic Back Gauge Spacer" and assigned to the same assignee as this case.

In conjunction with a cutting machine of such general characteristics, the present invention provides an automatic ejector mechanism arranged at the knife end. Such ejector is automatically actuated after the last transverse cut is made upon the stack. The function of the ejector is to move the last portion of the cut stack out from the machine through the feed-out end.

In accordance with this invention a plurality of finger-type members are arrayed to operate in unison. The fingers are swept through a slotted work delivery table, from beneath, upon completion of the cutting cycles. Novel apparatus is provided for automatic actuation of the ejector assembly to displace the end of the stack, out of the machine.

It is accordingly a primary object of this invention to provide novel ejector mechanisms.

Another object of the present invention is to provide more automatic ejector mechanisms in the form of a finger-like array.

A further object of the present invention is to put on cut stack ejector mechanism operative automatically at the end of the stack cutting cycles.

These and further objects of this invention will become more apparent in the following description of an exemplary embodiment. Thereof, illustrated in the drawings, in which:

FIGURE 1 is a side elevational view of a cutting machine incorporating the exemplary ejection mechanism as seen from the operator position with the central portion thereof broken away.

FIGURE 2 is an end elevational view of the cutting ma-

2

chine of FIGURE 1 at the "front" or "feed-out" position.

FIGURE 3 is a perspective view of the exemplary machine, with portions thereof removed for the purposes of clarity of illustration, and showing the exemplary ejector mechanism.

FIGURE 4 is an enlarged illustration of the ejector mechanism.

FIGURE 5 is an end view of the ejector of FIGURE 4 as seen from the right hand thereof.

FIGURES 1 and 2 show the side and "front" and elevations, respectively, of the cutting machine incorporating the invention cut stack ejector.

The "front" end, as is normally termed in such commercial machines, will be herein also termed the "feed-out" position, corresponding to the position on the right end of the machine seen in FIGURE 1, and as seen in elevation in FIGURE 2. The front portion of the stack of sheets, after being cut off, is fed out from the "feed-out" end.

The main column 100 of the machine supports the guide supports for the knife cutting assembly, as will be detailed hereinafter, as well as the frame section of the balance of the machine including the work table. The left side column 101 is an additional support for the machine and includes the circuit and relay panel for the electrical control system herein. Main column 100 serves also as an oil reservoir for the hydraulic serve components of the machine. The work table (not seen in FIGURES 1 and 2) is arranged at a small angle to the horizontal plane, the left side of the table as viewed from feed-out end of FIGURE 2 being raised above the right end.

A side gauge 102 is at the right side of the work table (FIGURE 2); the corresponding longitudinal side of the stacks of sheets rests against side gauge 102. Side gauge 102 is perpendicular to the tilted work table. A conveyor system 103 starts at tilted roller 104 adjacent the cutting position under knife assembly 105 and extends to horizontal roller 106. An idler roller 107 completes the circuit of the conveyor sheet 108.

A hood 110 is mounted above conveyor 103, covering up the external access to knife assembly 105 for safety purposes. Hood 110 is hinged at 111, providing a suitable protecting means with ready accessibility to the cutting position at the "feed-out" end of the machine. Hood 110 may be of sheet metal with transparent panes of glass or plexiglass. A safety switch (not shown) is actuated by hood 110 when opened up, shutting off the electrical control circuits of the machine, stopping the action of the knife assembly 105 and of the other sections as well. Thus, the safety hood 110 prevents accidents to fingers of the operator since the knife and the machine are stopped when the hood is opened.

A frame 112 extends from the main column 100 and serves to support conveyor assembly 103.

The cutting knife assembly 105 is shown in dotted lines, within the machine, in FIGURES 1 and 2. The general outline and correlation of the basic components 60 of cutting mechanism 105 as seen in these figures is as follows: The knife bar 115 is supported in suitable guides and carries the knife blade 116 at its lower cut-out section. Knife assembly 115, 116 is arranged at the angle with horizontal to coact normally with the work bed and stack carried at the same angle, for the purposes to be more fully described. Knife blade 116 is demountable from knife bar 115 for replacement or sharpening.

A front or knife clamp 117 is arranged contiguous to

and behind knife bar 115. Suitable control means are operated on clamp 117 to press it down on the front sector of a stack of sheets in the machine just prior to cutting by knife blade 116. The stack of sheets is held firmly adjacent the transverse cutting position wherein the reciprocable knife blade 116 effects the transverse cut, as is understood by those skilled in the art. A suitable torsion bar 118 and hydraulic cylinder 119 are associated with the clamp 117 for its motivation.

The back gauge 120 transverses the machine along its full operating length in the longitudinal direction. It is secured to the work table (see FIGURE 3). Back gauge 120 incorporates a vertical frame 121 that pushes the end of the stack of sheets on the work table forward to cutting blade 116. The back gauge 120 of the exemplary machine incorporates a series of fingers 122 of the back gauge clamp. The fingers 122 of the back gauge clamp are seen in progression in FIGURE 1 in view of the tilt of the back gauge with the horizontal. Their function is to press against the top layer of the back end of the stack of sheets in the cutting machine and firmly grip the whole back end of the stack or stacks throughout the cycles of the cutting program. In other words, the positive gripping of the stack or stacks on the work table by the fingers 122 of the back gauge clamp and the resting of the side of the stack against tilted side gauge 102 eliminates "walking" of the sheets on the stack and its angular dislocation due to the front clamp action (117).

It is thus practical to arrange the loading of the stacks from the side of the machine 125 (FIGURE 1). This is more efficient in production as the stacks or piles to be cut into book pages or wrappers, etc. are long, such as 40" to 60". These stacks are slid along the horizontal side work table 126 and across to the work bed of the machine (150—FIGURE 3) all from the machine side 125. The operator and the controls for the machine are arranged at side 125 for the progress of the cutting program on the sheets. Control panel 127 contains the start 128 and stop 129 control switches for operating the pump of the hydraulic system.

Electrical panel 130 contains the switches for controlling the operation of the back gauge with control button 131 for the forward movement, control button 132 for the reverse movement, and control button 133 for stop. These controls in panel 130 are manual over-rides by the operator for the action of the back gauge independent of the automatic programming of the machine operation. Similarly, there are two over-riding controls for the action of knife assembly 105; electrical control 134 arranged at the left side of the machine and control 135 at the right side of the operating position. Either one of these switches 134, 135 over-rides the automatic programming action of the knife assembly 105 whereby the operator can actuate knife blade 116 into cutting whenever desired. Similarly, a pedal for operating the hydraulic action of the back gauge clamp is arranged at 136, and pedal for operator actuation of the front clamp 117 and 137.

A safety hood 140 is provided over the work bed, the work thereon, and the back gauge 120. Hood 140 has a handle 141 to lift it out of the way when loading, unloading or otherwise by the operator. A safety switch (not shown) is actuated upon opening of hood 140, whereby all elements of the cutting machine are stopped from forward movement or actuation. This safety feature is important to the operator. A large panel of glass or plexiglass may be arranged in hood 140 which is otherwise of sheet metal.

CUTTING MACHINE—MAIN OPERATING UNITS

FIGURE 3 is a perspective illustration of the exemplary embodiment of the cutting machine showing the essential operating units and their correlation. For the purposes of clarity of illustration in FIGURE 3, the protective hoods, the conveyor system 103, the side table

126, the main supports and housing of the machine, and the start-stop programming control unit have all been omitted from this figure. Also, a stack or stacks of sheets is not shown on the work table to simplify the illustration but will readily be understood by those skilled in the art.

(a) *Tilted work table*.—The work table 150 is seen to extend from the rear of the machine (at the right—FIGURE 3) longitudinally through the machine to the "front" of feed-out end adjacent knife assembly 105. The rear of work table 150 is supported on a hollow frame member 151, in turn supported on main upright 101. The front end (left—FIGURE 3) of work table 150 is supported directly on the inclined surface 152 of main column 100. Work table 150 is comprised of a series of spaced parallel flat bars 155. The spacing between the bars 155 is substantially equal to the width of the bars in the transverse direction. In a practical embodiment, the transverse width of table bars 155 may be of the order of $\frac{1}{2}$ ", $\frac{3}{4}$ ", or 1"; and the spaces between these bars of the same dimension as the selected bar widths. It will now be apparent that the work table area that the stack rides on has the order of 50% less frictional contact with the work bed as compared to a solid work bed of the prior art. Thus, the paper stack is pushed by the back gauge 120 along work table 150 with a substantially less frictional drag.

Also it is important to note that cutting and trimmings of paper and other debris, due to the operation of the machine on paper stacks, readily fall through the open spaces between the parallel bars 155 comprising the work table. The work table 150 is accordingly readily maintained clean, and has a reduced friction for the stack movements thereon. Such reduced friction to the movements of the paper stack on the work table further enhances the maintaining of the stack in its vertical alignment and minimizes any tendency of the stack to "walk" or otherwise distort when being operated upon. Another important purpose of the spaced bar work table 150 construction is to provide room for the lower movable members of the back gauge clamp, and the fingered ejector apparatus hereof.

The work table 150 and the inclined surface 152 of column 100 upon which it is mounted are inclined at a fixed small angle to the horizontal plane of the machine, which angle we shall for purposes of reference refer to as θ . In practice, the angle θ actually used may range from 1° to 20° , but this is optional. Even a small angle of tilt to horizontal for θ has been found to attain satisfactory results herein. In one practical embodiment θ equalled 3° .

The back gauge 120 and its associated back gauge clamp 122, 123 are movably mounted on work table 150 and parallel thereto at the same inclined angle to the horizontal. Similarly, the knife apparatus 105 including front clamp 117 and the knife assembly 115, 116 are mounted at the same angle θ to the horizontal plane, rendering the cutting blade assembly parallel to the surface of cutting table 150. The bottom cutting edge of blade 116 is further inclined to the horizontal to effect a guillotine type of cut.

(b) *Back gauge*.—The back gauge assembly 120 moves longitudinally of the machine and along the work table 150. The function, details and operation of the back gauge 120 and the associated back clamp 122, 123 is set forth in said parent case at columns 9-11 in the heading "Back Gauge and Back Gauge Clamp" in connection with the description of FIGURES 18, 19 and 20 thereof. Back gauge 120 comprises vertical pusher frame 121 that abuts the rear end of the stacked sheets. The frame portion 121 is segmented and projects through the openings in work table 150 between horizontal bars 155. A bracket 156 extends from the bottom of the back gauge, beneath work table 150, and is secured thereto.

The back gauge 120 is actuated along the work bed

150 in the forward and rearward direction through hydraulic cylinder 157 by piston rod 158 extending from cylinder 157 and a pantograph linkage 160. The pantograph 160 linkage between hydraulic cylinder 157 and back gauge 120 (at bracket 156) permits a long swing of the piston rod 158 to subtend the working excursion of back gauge 120 on work table 150. In a practical embodiment, such swing was 60". It is to be noted that the hydraulic cylinder 157 is held horizontal and longitudinal of the machine, parallel to the direction of movement of back gauge 120. It is important to maintain piston rod 158 in a horizontal plane to prevent distortion and malfunctioning of its hydraulic drive for the back gauge. This is accomplished by pantograph 160 in a manner set forth in detail in said parent case in connection with the description of FIGURES 21 and 22 thereof, under the heading "Back Gauge Drive Mechanism."

(c) *Back gauge clamp.*—The back gauge clamp comprises movable fingers 122, 122 projecting between the open spaces of the vertical bars of the pusher section 121 of back gauge 120. The fingers 122, 122 are operable in the vertical direction, within vertical frame 121, by means detailed in said parent case in connection with the description of FIGURES 18, 19 and 20 thereof, under the heading "Back Gauge and Back Gauge Clamp." A series of stationary fingers 123, 123 are located beneath the movable fingers 122, 122. The top surface of stationary fingers 123, 123 is a small distance above the plane of work table 150. The stationary fingers 123, 123 of the back gauge clamp are arranged in the interstices of bars 155, 155 of table 150 and are secured to a projecting portion of the back clamp structure 120.

When the movable fingers 122, 122 of the back gauge clamp are activated downwardly, they grip the tail end of the stack or stacks of sheets against the pusher surface 121 of the back gauge, pressing the stacks between the coacting pairs of fingers 122, 123. The intensity of force exerted by this clamp 122, 123 of the back gauge on the stack is made at least equal to, and preferably greater than, the intensity of force exerted by the front clamp 117 at the forward end of the stack. In other words, the clamp 117 used for cutting purposes at the front stack end must not be able to loosen the stack of sheets that is held by back gauge clamp 122, 123 under any conditions of operation. The back gauge clamp 122, 123 is arranged to exert a powerful grip and travels with the back gauge 120 forming, in effect, a travelling table for the paper stack as it is moved forward to the successive transverse cutting positions.

Thus, the stack or parallel stacks of sheets will not become distorted, and the printing on successive sheets will remain in accurate vertical alignment in all cutting operations by the knife 115, 116. As already stated, such clamping of the rear end of the stack permits the motivation of the back gauge, and the speed of the operating cycle between cuts, to be faster than heretofore possible with practical commercial cutting machines. With the exemplary machine, there is no danger of distorting or "walking" of the pile of sheets; particularly in view of the combination of the back gauge clamp 122, 123 with the tilted work table. Such combination virtually secures the stack in proper operating alignment regardless of possible distortions due to speed of travel, deceleration of the stack or operation of the knife assembly 105 and its associated clamp 117. It also becomes unnecessary for the operator to remain at the feedout position of the work table at the cutting position for readjusting the stack that may otherwise have become distorted.

The cycling and motivation of the back gauge, through hydraulic cylinder 157, is controlled in the usual manner for automatic cutting machines such as on a start-stop programming device (as described in Patents Nos. 2,487,031 and 2,053,499), or otherwise.

The side gauge 102 extends perpendicular from the

plane of work table 150 and the paper stacks rest against side gauge 102 due to the tilting of the table 150.

(d) *Knife assembly.*—The cutting knife assembly 105 is mounted adjacent the front or "feed-out" end of the machine. The vertical main supports 180, 181 for the cutting assembly 105 are secured to the inclined surface 152 of the main column 100. Guide supports 182, 183 for containing the movement of knife assembly 115, 116 and clamp 117 are secured to and otherwise bolted to the vertical supports 180, 181. The top beam 184 for the assembly 105 is supported across the supports 180, 183 as more clearly shown in FIGURE 4. The knife bar 115 is reciprocably mounted in the guide supports 182, 183 and actuated by a crank mechanism extending from the gear mechanism box 185. Details of the knife drive mechanism within gear box 185 are shown and described in said parent case in connection with FIGURES 6 through 13 thereof.

A draw bar 186 extends from a crank within gear box 185 and is linked to ear 187 extending from knife bar 115 through link 188 pivoted at 189. The opposite end of knife bar 115 is pivotally supported from the top cross beam 184, through link 190 connecting rear ear 191 of knife bar 115 to the pivoted end 192 of beam 184. Pivot 192 is preferably a bearing surface, to minimize friction; as is the pivot 193 between link 190 and the knife bar. A heavy spring 195 is mounted within a cavity of cross beam 184 and arranged in a further linkage to the knife bar 115, including elements 196, 197, 198 and 199 shown in more detail in FIGURES 4 and 5 hereinafter.

The purpose of the heavy spring 195 and its associated linkages with knife bar 115 is to normally bias or otherwise maintain knife bar 115 in its upward, non-operative position. In other words, spring 195 is arranged to keep the knife blade 116 in knife bar 115 normally at all times when non-operating in the upward position so as not to cause injury to the operator or stack should any component of the knife mechanism 105 or other part of the drive become broken or inoperative. Further advantages and details of this construction are set forth hereinafter.

Actuation of the knife draw bar 186 by the crank mechanism in gear box 185 is on a cyclic basis under the control of the start-stop programming system. The hydraulic cylinder 119 for actuating front clamp 117 is seen in dotted lines in FIGURE 3. Cylinder 119 is supported in cross-beam 184. The torque bar 118 is connected to front clamp 117 for the purpose of keeping the clamp in the position parallel with the work table 150 under all clamping operations despite the thickness of height of the stack of sheets. Further details of the operation of torque bar 118 and its associated mechanism are described in connection with FIGURES 14 through 17 of said parent case under the heading "Front (Knife) Clamp System."

Ejector Mechanism

At the forward or feed-out location of the cutting machine is located an ejector mechanism whereby the last remaining portion of the stack is mechanically moved forward from the work table 150 into the conveyor 108 (FIGURES 1 and 2). Shown in dotted lines in FIGURE 3 is a shaft 215 rotatably supported in the frame of the machine. A pulley 216 is secured to shaft 215. A cable 217 is arranged to rotate shaft 215 counterclockwise when pulled downwardly by actuating bar 218. Actuating bar 218 is pivoted at 219 and is controlled to operate downwardly when the back gauge is moved to a predetermined position at the end of the program of cutting.

Rod 218 may be actuated electrically through a solenoid or mechanically by a suitable element under the control of the position of the back gauge after the last cut on the stack. The downward movement of cable 217 when effectuated rotates shaft 215 and the series of spaced fingers 220 secured to rod 215. The ejector fingers 220 are positioned to be moved between the spaces of bars 155 of table 150 and engage the end portion of

the cut paper stack. It moves such stack portion outward of the machine into the conveyor 108.

The position of the back gauge for actuation of lever 218 and the ejecting mechanism herein is preferably when the back gauge is already in its return rearward movement and has already moved back toward its starting position by a predetermined amount. Actuation of lever 218 and ejecting fingers 220 will thus operate upon the last portion of the cut stack without interference from the back gauge 120 and back gauge clamp 122, 123. The ejector is operated after the last cutting stroke of the knife assembly 105 and when the clamp 117 and knife 115, 116 are in their upward position. The remaining stack portion is moved forward out of the machine. The back gauge, when at a predetermined further position in its return movement, de-energizes the ejector actuating lever 218. The spring biased cable 217 thereupon returns to the initial position, as indicated in FIGURE 3.

The machine of FIGURE 3 is further strengthened by cross-bars 221, 222, at 223 at the back side portion forming triangular strut 224. Further cross bars 225, and 226 strengthen the vertical structure between the main vertical supports 100, 101. Additional strengthening struts and cross bars, supporting members and the like are, of course, optional. The location of the mechanical, electrical and hydraulic control elements are a matter of choice, as are the locations of the control levers, pedals and switches.

Reference is now made to FIGURES 4 and 5, which are enlarged detail views of the exemplary ejector mechanism. When the back gauge 120 has moved back, by a predetermined distance, after the last cut, a solenoid 475 is energized. Energization of solenoid 475 attracts into it armature member 476, secured to ejector lever 218 by pin 477. The ejector lever 218 is pivoted to a stationary bracket 478 by pin 479. The opposite end 480 of lever 218 secures the end of cable 217. The downward attraction of armature 476 (FIGURE 5) causes cable 217 to be drawn downwardly to rotate ejector shaft 215 at pulley 216. The spring fingers 220, 220 are secured to the rod 215 and, are rotated clockwise from their normal out-of-the-way position. It will now be apparent that the clockwise rotation of fingers 224 move them between the spaces of table bars 155.

The fingers 220 thereupon abut the portion of the stack remaining adjacent the feed-out position, where the ejector is situated. The fingers 220, 220 get behind the stack portion that was left under the main clamp, and push it forward into the conveyor 103 (FIGS. 1, 2). It is to be understood that the main clamp 117 had already been retracted upwardly and out-of-the-way, prior to such ejection action. Furthermore, the back clamp 120 had already been returned, on its way toward its start, (to right, FIG. 3), to permit the spring fingers 220 to move under the table through bars 155 for the ejection action. The timing thereof is controlled by the energization of the solenoid 475.

After sufficient interval to permit the full ejection by the clockwise rotation of the ejection fingers 220, and as the back gauge has moved further towards its rear (start) position, solenoid 475 is de-energized. The spring fingers 220 thereupon are returned to their lower position, shown in solid lines in FIGURE 5 by the biasing action of the springs 485, 485 secured beneath the table 150. Cable 217 is moved to its normal unactivated downward position, and lever 218 is returned to its unactuated position for the next ejection cycle.

It is to be understood that in place of the solenoid 475 other actuation means are equally feasible. One such form is a mechanical linkage arrangement from a movable machine member (such as the back gauge) to the cable 217 or directly to the ejector shaft 215, all in proper cycling and timing with the other aspects of the cutting

operation. The reverse or resetting of such displaced cable may thereupon be effected by a solenoid.

It is to be understood that the exemplary ejector mechanism herein described and illustrated, and its associated features and component sections may take various other forms and arrangements within the broader spirit and scope of the invention as defined in the following claims.

I claim:

1. A machine of the character described for successively cutting a stack of sheets transversely comprising a work table having spaced bars with intermediate slots for supporting the stack, a reciprocable knife assembly with a blade arranged transverse of said table for successively cutting forward portions of the stack when projected into the knife assembly, and ejector means arranged adjacent said knife assembly for abutting the last-cut portion of the stack and moving it past the knife assembly, said ejector means including a plurality of finger-like elements movable through said spaced slots in the work table to effect ejection of the last-cut portion, and said elements being normally disposed on one side of said table so as not to interfere with movement of said stack during said successive cutting.

2. A machine as claimed in claim 1, further including a transverse member rotatably carrying said elements, a spring normally biasing said member to maintain said elements on said one side of the work table, and means for rotating said member against the spring bias to motivate said elements against the last-out stack portion and remove it from the knife assembly area after the cutting cycle.

3. A machine of the character described for cutting a stack of sheets comprising a work table for supporting the stack, a back gauge movable in controllable stages along said table having a face cooperable with the sheets, a knife assembly for successively cutting portions of the stack a clamp mounted with said back gauge for gripping the back portion of the stack of sheets, continuously in its motivations, said work table being composed of a plurality of spaced longitudinal bars, and ejector means arranged adjacent the feed-out end of the work table for abutting the last-cut portion of the stack and moving it off the work table, said means including a plurality of finger-like elements in an array movable between said spaced bars to effect the stack portion ejection and being normally disposed below said work table so as not to interfere with said stack in the course of successive cutting.

4. A machine of the character described for successively cutting a stack of sheets transversely comprising a work table for supporting the stack, said work table embodying a plurality of spaced longitudinal bars, a back gauge mounted transverse of and movable along said table with a face cooperable with the rear end of the stack of sheets, a reciprocable knife assembly with a blade arranged transverse of said table for successively cutting forward portions of the stack when projected into the knife assembly by said back gauge, and ejector means arranged adjacent the feed-out end of the work table for abutting the last-cut portion of the stack and moving it past the knife assembly and off the work table including a plurality of finger-like elements rotative as an array between said spaced bars to effect the stack portion ejection; a rotative means carried by said machine, said elements being carried by said means, and an actuator device for said rotative means whereby upon actuation thereof said elements effect rotation into abutment with said last-cut portion of the stack.

5. In a cutting machine having a knife assembly arranged over a work table, said work table being provided with a series of slots extending below said knife assembly, an ejector mechanism disposed below said work table and comprising ejector means, actuating means for said ejector means operative to move said ejector means through said slots and above said work table wherein said ejector means is normally disposed therebelow, and

wherein said ejector means is disposed to abut the rear surface of cut stock and to move said stock from below said knife assembly, upon being actuated.

6. In a device as set forth in claim 5, said ejector means comprising a rotative shaft and a plurality of spaced fingers carried thereon. 5
